UNITED STATES PATENT OFFICE

153,775

DESIGN FOR A PIG BANK

Samuel Dubiner, Toronto, Ontario, Canada

Application December 11, 1947, Serial No. 143,102

Term of patent 14 years

(Cl. D34—11)

To all whom it may concern:

Be it known that I, Samuel Dubiner, a citizen of the Dominion of Canada, residing in the city of Toronto, county of York, Province of Ontario, Dominion of Canada, have invented a new, original, and ornamental Design for a Pig Bank, of which the following is a specification, reference being had to the accompanying drawing, forming part thereof.

Fig. 1 is a perspective view of a pig bank showing my new design.

Fig. 2 is a top front perspective view.

Fig. 3 is a side elevation.

Fig. 4 is a rear elevation.

I claim:

The ornamental design for a pig bank, as shown.

SAMUEL DUBINER.
